UNITED STATES PATENT OFFICE

158,176

HAND BRUSH OR THE LIKE

Murphy A. Chesney, Knoxville, Tenn., assignor to Cheslan Brush Company, Inc., Knoxville,
Tenn., a corporation of Tennessee

Application December 31, 1948, Serial No. 150,501

Term of patent 14 years

(Cl. D9—2)

To all whom it may concern:

Be it known that I, Murphy A. Chesney, a citizen of the United States, residing at Knoxville, in the county of Knox and State of Tennessee, have invented a new, original, and ornamental Design for Hand Brushes or the like, of which the following is a specification, reference being had to the accompanying drawings, forming part thereof.

In the accompanying drawings:

Fig. 1 is an end elevational view of a hand brush or the like, showing my new design with the brush in open position.

Fig. 2 is a side elevation thereof;

Fig. 3 is an end elevational view thereof with the brush enclosed within the handle portion.

Fig. 4 is a top plan view of the brush; and

Fig. 5 is a top plan view of the head portion detached from the handle portion.

I claim:

The ornamental design for a hand brush or the like, substantially as shown.

MURPHY A. CHESNEY.
